UNITED STATES PATENT OFFICE.

GLENVILLE J. G. LACEY, OF KALAMAZOO, MICHIGAN.

VERTICAL WATER-TUBE BOILER.

Application filed May 8, 1922. Serial No. 559,326.

To all whom it may concern:

Be it known that I, GLENVILLE J. G. LACEY, a subject of the King of Great Britain, and a citizen of the Dominion of Canada, residing at the city and county of Kalamazoo, State of Michigan, have invented certain new and useful Improvements in Vertical Water-Tube Boilers, of which the following is a specification.

10. This invention relates to improvements in vertical water tube boilers, that might properly be called a modified vertical water tube boiler.

The objects of the invention are:

15. First, to provide an improved construction of water tube boiler in which the heat units developed in the firebox or furnace will be more effectively utilized.

Second, to provide an improved construction and arrangement of water tubes in a water tube boiler.

Objects pertaining to details and economies of construction and operation will definitely appear from the detailed description 25 to follow.

I accomplish the objects of my invention by the devices and means described in the following specification. The invention is clearly defined and pointed out in the claims.

30. A structure which is a preferred embodiment of my invention is fully illustrated in the accompanying drawing, forming a part of this application, in which:

Fig. I is a detail central sectional elevation view taken on line 1—1 of Figs. II and III, the boiler and tube portions being shown in full lines and the position of certain parts being indicated by dotted lines, the casing and partition walls and footings 40 being in section.

Fig. II is an enlarged plan view of the boiler and tube parts appearing in Fig. I, the casing and footings being omitted.

Fig. III is a detail sectional view through 45 the bridge wall taken on the irregular line 3—3 of Fig. I, showing the flue openings therethrough.

In the drawings the sectional views are taken looking in the direction of the little 50 arrows at the ends of the section lines and similar numerals of reference refer to similar parts throughout the several views.

Referring to the numbered parts of the drawing, 1 is the upper drum of a vertical 55 water tube boiler, 2 is the base and 3 the

usual water tubes between the base and upper drum. 4 is the usual casing surrounding the same. 5 is the firebox or furnace, preferably provided with an automatic stoker 6 with the ashpit 7 below. 8 the footings walls for supporting the boiler and 9 the bridge wall having a series of flue passages 10 therethrough for delivering heat and the products of combustion directly into the front of the boiler. 11 is the vertical partition extending from the base 2 up towards the top drum 1 to compel the products of combustion to ascend through the tubes, pass over the partition wall and then down to the flue opening 12, which leads to the 70 stack 13. These parts, with the exception of the bridge wall, are in a usual form of water tube boiler.

14 is an auxiliary header disposed transversely to the lower front portion of the upright tubes of the boiler and having a portion of the tubes 15 deflected and connecting therefrom to the top drum, and another portion 16 connecting from the base and deflected and connected to the said header 14. 17 is the front header of the boiler resting upon the front wall of the furnace, 18 a series of obliquely disposed water tubes extending from their front header 17 upwardly and rearwardly to the auxiliary header 14. A transversely disposed partition 20 divides the rear portions of the boiler tubes 18 into an upper and lower group affording a double passage for the products of combustion which pass directly up from the firebox 5, these water tubes being disposed directly above the firebox. An oblique casing 19 closes the top of the chamber within which the oblique water tubes are disposed, the same being closely 95 conformed thereto to retain and guide the heated products of combustion in close relation to the said pipes and deliver them through the passage way 14' above the header 14. A considerable part of the 100 products of combustion are delivered underneath the header because of the deflecting partition wall 20.

21 is a pipe connection to the bottom of the boiler. 22 is a blow out pipe from the bottom of the header 17, and 23 is a feed pipe connecting to the top of the header 17, the same being associated with the usual feed pipe 23' for delivering water to the main part of the boiler. 24 is a circulation 110

pipe from the header 14 to the top drum 1 of the boiler. 25 is a water column gage at the top drum of the boiler.

I have shown my improved water tube boiler in the form preferred by me, but desire to state that it can be considerably varied in its details without departing from my invention. I desire to claim the same in the precise form in which I have illustrated it and also desire to claim the same broadly as pointed out in the appended claims.

Having thus described my invention, what I claim as new and desire to secure by Letters Patent, is:

- 15 1. The combination in a vertical water tube boiler of a head, a base, vertical water tubes connecting the same, a casing and partition wall for forming the passage therethrough for products of combustion, a furnace disposed to one side thereof, an auxiliary transverse header above the said furnace and connecting to a portion of the vertical tubes in the front of said boiler whereby the water is circulated up through the said header, a header at the front of the said furnace, inclined water tubes between the front header and the auxiliary header, a dividing partition at the upper rear portion of said water tubes, a casing surrounding the same, 20 a circulation pipe from the said auxiliary header to the head of the said boiler, feed pipe delivering to the top of the said front header, and a bridge above the said furnace and beneath the auxiliary header with suitable 25 passages therethrough to divide and distribute the products of combustion from the firebox, all coacting for the purpose specified.
- 30 2. The combination in a vertical water tube boiler of a head, a base, vertical water tubes connecting the same, a casing and partition wall for forming the passage therethrough for products of combustion, a furnace disposed to one side thereof, an auxiliary transverse header above the said furnace and connecting to a portion of the vertical tubes in the front of said boiler whereby the water is circulated up through the said header, a header at the front of the said furnace, inclined water tubes between the front header and the auxiliary header, a dividing partition at the upper rear portion of said water tubes, a casing surrounding the same, 35 feed pipe delivering to the top of the said front header, and a bridge above the said furnace and beneath the auxiliary header with suitable passages therethrough to divide and distribute the products of combustion from the firebox, all coacting for the purpose specified.
- 40 3. The combination in a vertical water tube boiler of a head, a base, vertical water tubes connecting the same, a casing and partition wall for forming the passage therethrough for products of combustion, a furnace disposed to one side thereof, an auxiliary transverse header above the said furnace and connecting to a portion of the vertical tubes in the front of said boiler whereby the water is circulated up through the said header, a header at the front of the said furnace, inclined water tubes between the front header and the auxiliary header, a casing surrounding the same, 45 feed pipe delivering to the top of the said front header, and a bridge above the said furnace and beneath the auxiliary header with suitable passages therethrough to divide and distribute the products of combustion from the firebox, all coacting for the purpose specified.
- 50 4. The combination in a vertical water tube boiler of a head, a base, vertical water tubes connecting the same, a casing and partition wall for forming the passage therethrough for products of combustion, a furnace disposed to one side thereof, an auxiliary transverse header above the said furnace and connecting to a portion of the vertical tubes in the front of said boiler whereby the water is circulated up through the said header, a header at the front of the said furnace, inclined water tubes between the front header and the auxiliary header, a casing surrounding the same, 55 feed pipe delivering to the top of the said front header, and a bridge above the said furnace and beneath the auxiliary header with suitable passages therethrough to divide and distribute the products of combustion from the firebox, all coacting for the purpose specified.
- 60 5. The combination in a vertical water tube boiler of a head, a base, vertical water tubes connecting the same, a casing and partition wall for forming the passage therethrough for products of combustion, a furnace disposed to one side thereof, an auxiliary transverse header above the said furnace and connecting to a portion of the vertical tubes in the front of said boiler whereby the water is circulated up through the said header, a header at the front of the said furnace, inclined water tubes between the front header and the auxiliary header, a casing 65 surrounding the same, feed pipe delivering to the top of the said front header, and a bridge above the said furnace and beneath the auxiliary header with suitable passages therethrough to divide and distribute the products of combustion from the firebox, all coacting for the purpose specified.
- 65 6. The combination in a vertical water tube boiler of a head, a base, vertical water tubes connecting the same, a casing and partition wall for forming the passage therethrough for products of combustion, a furnace disposed to one side thereof, an auxiliary transverse header above the said furnace and connecting to a portion of the vertical tubes in the front of said boiler whereby the water is circulated up through the said header, a header at the front of the said furnace, inclined water tubes between the front header and the auxiliary header, a casing 70 surrounding the same, a circulation pipe from the said auxiliary header to the head of the said boiler, and feed pipe delivering to the top of the said front header.

75 4. The combination in a vertical water tube boiler of a head, a base, vertical water tubes connecting the same, a casing and partition wall for forming the passage therethrough for products of combustion, a furnace disposed to one side thereof, an auxiliary transverse header above the said furnace and connecting to a portion of the vertical tubes in the front of said boiler whereby the water is circulated up through the said header, a header at the front of the said furnace, inclined water tubes between the front header and the auxiliary header, a casing surrounding the same, a circulation pipe from the said auxiliary header to the head of the said boiler, and feed pipe delivering to the top of the said front header.

80 5. The combination in a vertical water tube boiler of a head, a base, vertical water tubes connecting the same, a casing and partition wall for forming the passage therethrough for products of combustion, a furnace disposed to one side thereof, an auxiliary transverse header above the said furnace and connecting to a portion of the vertical tubes in the front of said boiler whereby the water is circulated up through the said header, a header at the front of the said furnace, inclined water tubes between the front header and the auxiliary header, a casing surrounding the same, a circulation pipe from the said auxiliary header to the head of the said boiler, and feed pipe delivering to the top of the said front header.

85 6. The combination in a vertical water tube boiler of a head, a base, vertical water tubes connecting the same, a casing and partition wall for forming the passage therethrough for products of combustion, a furnace disposed to one side thereof, an auxiliary transverse header above the said furnace and connecting to a portion of the vertical tubes in the front of said boiler whereby the water is circulated up through the said header, a header at the front of the said furnace, inclined water tubes between the front header and the auxiliary header, a casing surrounding the same, feed pipe delivering to the top of the said front header, and a bridge above the said furnace and beneath the auxiliary header with suitable passages therethrough to divide and distribute the products of combustion from the firebox, all coacting for the purpose specified.

90 7. The combination in a vertical water tube boiler of a head, a base, vertical water tubes connecting the same, a casing and partition wall for forming the passage therethrough for products of combustion, a furnace disposed to one side thereof, an auxiliary transverse header above the said furnace and connecting to a portion of the vertical tubes in the front of said boiler whereby the water is circulated up through the said header, a header at the front of the said furnace, inclined water tubes between the front header and the auxiliary header, a casing 95 surrounding the same, a circulation pipe from the said auxiliary header to the head of the said boiler, and feed pipe delivering to the top of the said front header.

surrounding the same, feed pipe delivering to the top of the said front header, and a bridge above the said furnace and beneath the auxiliary header with suitable passages there-
5 through to divide and distribute the products of combustion from the firebox, all co-
acting as specified.

7. The combination in a vertical water tube boiler of a head, a base, vertical water tubes connecting the same, a casing and parti-
10 tion wall for forming the passage there-
through for products of combustion, a fur-
nace disposed to one side thereof, an aux-
iliary transverse header above the said fur-
nace and connecting to a portion of the vertical tubes in the front of said boiler where-
15 by the water is circulated up through the 35
said header, a header at the front of the said furnace, inclined water tubes between the front header and the auxiliary header, a cas-
ing surrounding the same, and feed pipe de-
livering to the top of the said front header, 40
all coacting as specified.

15 8. The combination in a vertical water tube boiler of a head, a base, vertical water tubes connecting the same, a casing and parti-
20 tion wall for forming the passage there-
through for products of combustion, a fur-
nace disposed to one side thereof, an aux-
iliary transverse header above the said fur-
nace and connecting to a portion of the vertical tubes in the front of said boiler where-
25 by the water is circulated up through the 35
said header, a header at the front of the said furnace, inclined water tubes between the front header and the auxiliary header, a di-
viding partition at the upper rear portion of said water tubes, a casing surrounding the same, and feed pipe delivering to the top of the said front header, all coacting as speci-
fied.

25 9. The combination in a vertical water tube boiler of a head, a base, vertical water tubes connecting the same, a casing and parti-
30 tion wall for forming the passage there-
through for products of combustion, a fur-

nace disposed to one side thereof, an aux-
iliary transverse header above the said fur-
nace and connecting to a portion of the vertical tubes in the front of said boiler where-
35 by the water is circulated up through the 35
said header, a header at the front of the said furnace, inclined water tubes between the front header and the auxiliary header, a cas-
ing surrounding the same, and feed pipe de-
livering to the top of the said front header, 40
all coacting as specified.

10 9. The combination with a vertical water tube boiler of an auxiliary transverse header coupled into the vertical tubes thereof, a front header and inclined tubes from the 45 front header to the auxiliary header, a di-
viding partition for the rear portion of said tubes, and a furnace disposed below the said inclined tubes, all coacting as specified.

10 10. The combination with a vertical water tube boiler of an auxiliary transverse header coupled into the vertical tubes thereof, a front header and inclined tubes from the front header to the auxiliary header, and a furnace disposed below the said inclined 55 tubes, all coacting as specified.

In witness whereof, I have hereunto set
my hand and seal.

GLENVILLE J. G. LACEY. [L.S.]
